Aloha, Oreg. 97006

Filed June 17, 1970, Ser. No. 23,534

Term of patent 14 years

Int. Cl. D8—03

U.S. Cl. D8—234

FIG. 1 is a perspective view of two tree brackets of my design showing them mounted on trees, and each equipped with one form of supporting arm, wherein a plank is shown resting on the arms;

FIG. 2 is a side elevational view of my tree bracket on a scale larger than that of FIG. 1, and showing it equipped with the same arm as shown in FIG. 1;

FIG. 3 is a top plan view of the bracket and arm of FIG. 2;

FIG. 4 is a bottom view of the bracket and arm of FIG. 2;

FIG. 5 is a face-on view of the bracket and arm of FIG. 2; and

FIG. 6 is a rear view of the bracket shown in FIG. 2.

The broken lines are shown for illustrative purposes only.

I claim:

An ornamental design for a tree bracket, as shown and described.
